2,388,494

METHOD OF AND APPARATUS FOR
COATING STRIPSWalter P. Osgood, Malden, Mass., assignor to
Boston Machine Works Company, Lynn, Mass.,
a corporation of Massachusetts

Application August 20, 1941, Serial No. 407,593

10 Claims. (Cl. 117—68)

This invention relates to a method of and a means for applying coating to both faces of a strip of indeterminate length. While applicable to strips in general, it relates more particularly to strips of braided or plaited jute strands such as are used in making rope soles for shoes. Such strips have, in the past, been made into soles by being folded and wound upon themselves and then stitched so that the sinuous opposite edges of the strip form the surfaces of the sole. More recently, the convolutions of each strip have been cemented together in order to save time in manufacturing soles.

In forming a rope sole for a shoe of a given size and width, a definite length of strip is required. The proper length is cut off from a strip of indeterminate length and is folded or wound upon itself in successive convolutions in such a manner as to form the proper shape for a shoe sole. In order to hold the convolutions together, the faces of the strip are coated with a suitable cement, such as a latex preparation, the strip being folded and wound into the form of a sole while this cement is still in its adhesive state. It is desirable that the final or outer convolution of the sole have its outer face free from cement since such outer face constitutes the boundary edge of the sole itself.

It is an object of the present invention to provide apparatus for applying coating to both opposite faces of a strip, the coating on one of these faces being interrupted at predetermined intervals so as to leave an uncoated area on one face which will be the uncoated outer edge of a shoe sole after the strip has been wound into the shape of a sole.

As it is also desirable that the faces of the rope sole be free from cement, the apparatus hereinafter described is preferably formed to apply to each coated face of the strip a band of 40 coating material or cement which is narrower than the width of the strip itself, so that it does not extend to either edge of the strip.

It is a further object of the invention to provide apparatus for the purpose described which is arranged in such a way as to economize on floor space and which is easily set up, operated and adjusted.

For a more complete understanding of the invention, reference may be had to the following description of certain embodiments thereof and to the drawings, of which—

Figure 1 is an end elevation of an apparatus embodying the invention;

Figure 2 is a plan view of the same;

Figure 3 is a sectional view on lines 3—3 of Figures 1 and 2;

Figure 4 is a fragmentary, sectional view on line 4—4 of Figure 2 showing the strip supporting wheel in a different position from that shown in Figure 3;

Figure 5 is a fragmentary, sectional view on line 5—5 of Figure 4; and

Figure 6 is a fragmentary elevation of a portion of the apparatus shown in Figure 1, on a larger scale.

The apparatus may be mounted on a suitable base 10 and may comprise a casting 12 which may be of hollow box-like formation for use as a reservoir for certain kinds of liquid coating materials. In the present instance, however, a pool of latex cement is preferably maintained in a receptacle 14 by connection through a pipe 16 to a suitable constant-level source (not shown) such as an inverted bottle supported with its mouth in a pool communicating with the pipe 16. Partially submerged in the pool of cement in the receptacle 14 is a coating roll 18 which, as indicated in Figure 5, may be provided with a pair of cylindrical coating elements 20 and 22, which are axially spaced. As shown, these elements are of greater diameter than the remainder of the roll and are preferably narrower than the width of the strip 24 which is to be coated.

Directly over the coating element 20 is mounted a strip-supporting wheel or disk 30 having a periphery approximately of the same width as that of the strip 24. The circumference of the wheel 30 is made equal to the length of strip required for a single shoe sole. This wheel is spaced above the coating element 20 by a distance approximately equal to the thickness of the strip 24, so that when the strip is fed between the wheel 30 and the element 20, it is pressed against the latter so as to ensure positive kissing engagement therewith, whereby a film of cement is transferred from the element 20 to the under face of the strip 24. A doctor 28 is mounted adjacent to the peripheries of the elements 20 and 22 to regulate the thickness of the films of cement carried thereby. A portion 32 of the periphery of the wheel 30 is inwardly offset, so that when this portion of the periphery is opposite the element 20, the spacing is considerably greater than the thickness of the strip, as indicated in Figure 4. The length of the offset portion 32 of the periphery is determined by the length of strip required for the outermost convolution of the strip when made

into a shoe sole. A suitable leaf spring 34 may be mounted to project toward the nip between the element 20 and the wheel 30, this spring being biased to press the strip 24 upward against the periphery of the wheel 30. Hence, when the offset portion 32 of the periphery is opposite to the element 20, the spring 34 holds the strip 24 out of contact with the coating element 20. As a result, there are periodical gaps in the band of coating applied to the strip by the element 20, these gaps being equal in length to the offset portion 32 of the periphery of the wheel 30.

The guide wheel 30 may be supported by any suitable means such as a pair of standards 38 having a vertically adjustable cross-bar 40 in which is journaled a shaft 42 for the wheel 30. Suitable means, such as a pair of screws 44, supported by brackets 46 on the standards 38, may be provided for holding the wheel 30 in its vertically adjusted position. The wheel 30 is easily replaceable by similar wheels of different diameters according to the different lengths of strip required for shoe soles of various sizes.

After one face of the strip 24 has been coated, as hereinbefore described, it is desirable to apply coating to the opposite face. To this end, the strip is led around the periphery of the wheel 30, after passing the coating element 20, with its uncoated face in contact with the wheel. As shown in Figure 3, the strip 24 passes from the periphery of the wheel 30 to a tilted, idle, guide pulley 50. The lowermost point of the guide pulley is substantially on a level with the lowermost point of the wheel 30. As shown in Figures 1 and 2, the guide pulley 50 is offset from the plane of the wheel 30 sufficiently to guide the strip 24 in a path parallel to the portion of the strip, approaching the nip between the element 20 and the wheel 30. In passing from the idle guide pulley 50 to the coating element 22 of the roll 18, the strip 24 is twisted through a half turn, so that when it reaches the element 22, its uncoated side will be presented to this element to receive the coating therefrom. Directly above the coating element 22 is a suitable feed wheel 52 which, as indicated in Figure 5, is preferably provided with a knurled periphery having a series of points 54 adapted to sink into the face of the strip so as to ensure a positive feeding of the strip. The feed wheel 52 is mounted on a driven shaft 56 which is supported by an arm 60, which is rockable to raise the feed wheel clear of the strip 24.

As shown in Figure 1, a gear wheel 62 is mounted on the shaft 56, this gear wheel meshing with a gear wheel 64 mounted on a shaft 66 which also carries a pulley wheel 68. The shaft 66 extends across the casting 12 and drives the coating roll 18. The pulley 68 is connected by a suitable train of belts and pulleys, indicated generally at 70, to a pulley 72 mounted on the shaft of a suitable motor 74 supported on a frame 76, or to any other suitable source of power. The pulleys in the train 70 can be readily replaced, if desired, by pulleys of different sizes to alter the speed ratios between the motor and the shafts which drive the feed wheel 52 and the coating roll 18.

The arm 60 is rockable about a pivot 80 to permit the operator to lift the feed wheel 52 clear of the strip 24. The arm 60 is normally pressed toward its operative position by its own weight and also by a coiled spring 82. The space between the feed wheel and the coating element 22 is determined by an adjustable stop element 84 carried by the arm 60.

The casting 12 may be provided with a removable cover 86 which is rockable about the pivot 80 and is normally held in its closed position by a pair of screws and thumb nuts 88. When the cover is swung upward, an abutment element 89 thereon supports the shaft 56 and its arm 60. Suitable guides 90 are provided to ensure proper registration of the strip 24 with the periphery of the wheel 30. Guides 92 are also provided to maintain the strip properly aligned between the feed wheel 52 and the coating element 22. A suitable guide 94 may also be provided to guide the strip 24 as it comes from a bale toward the nip between the wheel 30 and the coating element 20.

I claim:

1. A method of coating strip material on both sides, which comprises continuously feeding a strip of indeterminate length in the form of a loop, applying coating material to one face of the strip at a point near the beginning of the loop, twisting the traveling strip through a half-turn, and applying coating material to the opposite face of the strip at a point beside the point where the first coating is applied.

2. A method of coating both sides of strip material, which comprises feeding continuously a strip of indeterminate length, applying a film of liquid intermittently to the under face of said strip at a predetermined point in its travel, leading the strip thence in a loop and twisting it through a half-turn to invert the same, and thereafter applying a film of liquid continuously to the under face of said strip at a location adjacent to that at which the first film is applied.

3. A method of partially coating strip material, which comprises feeding a strip of indeterminate length past a coating station with one face of the strip lowermost, intermittently applying coating material to the lowermost face of said strip at said coating station, causing said strip to describe a loop and twist a half-turn so as to return to said station with its other face lowermost, and continuously applying coating material to said other face at said station.

4. Apparatus for coating a strip, comprising a coating device, means for continuously feeding a strip, means for guiding said strip past said device with one face in operative contact therewith, means for separating said traveling strip from said device at predetermined intervals whereby spaced portions of the strip remain untreated by said device, means for guiding said strip back to said device through a path of predetermined length, and means for presenting the other face of said strip for operative contact with said device.

5. Apparatus for coating a strip, comprising a coating roll, means for feeding a strip of indeterminate length past and in contact with said roll to apply coating to one face of said strip, means for guiding said strip to present its other face for engagement with said roll, and means for periodically interrupting the contact of one of said faces with said roll.

6. Apparatus for coating a strip, comprising a coating roll rotatable about a horizontal axis, means for feeding a strip of indeterminate length horizontally with its under face in kissing engagement with the top of the roll, means for guiding said strip in a loop path to present the other side thereof for kissing engagement with said roll, and means for periodically interrupting the engagement of one of said faces with said roll.

7. Apparatus for coating a strip, comprising a coating roll rotatable about a horizontal axis, a rotatable guide wheel above said roll having a periphery of predetermined length and an axis of rotation parallel to that of said roll, said wheel being spaced above said roll by approximately the thickness of said strip, means for feeding said strip between said roll and wheel whereby said strip is pressed into positive contact with said roll to receive coating on one face thereof, said wheel having a portion of its periphery inwardly offset for periodic interruptions in the contact of said face of the strip with said coating roll, and means for guiding said strip back to said roll to present the other face for contact with said roll.

8. Apparatus for coating a strip, comprising a coating roll rotatable about a horizontal axis, said roll having two axially spaced cylindrical elements for applying coating, a guide wheel mounted over one of said elements, a feed wheel mounted over the other said element, said wheels being spaced above said elements just enough to permit feeding the strip between them, said guide wheel having a portion of its periphery inwardly offset to permit periodic disengagement of the strip from the roll element beneath the guide wheel, and means for twisting the strip through

half a turn as it leaves the guide wheel so as to present the other face of the strip to the roll element beneath the feed wheel.

5 9. Apparatus for coating a strip, comprising a coating roll rotatable about an axis, a guide wheel rotatable about a parallel axis and spaced from said roll by a distance substantially equal to the thickness of said strip, said guide wheel having a portion of its periphery inwardly offset to provide a greater spacing between said wheel and roll during a portion of each revolution of the wheel, spring means mounted adjacent to the nip between said wheel and roll and arranged to press the strip against the periphery of said wheel, and means for continuously feeding said strip.

10 15 10. Apparatus for coating a strip, comprising means for delivering a coating substance to strip material traveling in laterally separated paths, means for propelling a strip in one of such paths in receiving relation to said delivering means, and guide means constructed and disposed to lead the strip in a loop from said path to another one of the first-mentioned plurality of paths in receiving relation to said delivering means; the strip being twisted in its passage from said guiding means to the said other path so as to present its opposite side to the delivering means.

20 25 WALTER P. OSGOOD.
